UNITED STATES PATENT OFFICE.

RALPH S. ROBERTS, OF DETROIT, MICHIGAN, ASSIGNOR TO BRIGGS MANUFACTURING COMPANY, OF DETROIT, MICHIGAN, A CORPORATION OF MICHIGAN.

DESIGN FOR A DOOR HANDLE.

Application filed November 28, 1927. Serial No. 24,324. Term of patent 7 years.

To all whom it may concern:

Be it known that I, RALPH S. ROBERTS, a citizen of the United States of America, residing at Detroit, in the county of Wayne, and State of Michigan, have invented a certain new, original, and ornamental Design for Door Handles, of which the following is a specification, reference being had therein to the accompanying drawings, forming part thereof, in which—

Fig. 1 is a perspective view of a handle embodying my invention; Fig. 2 is a top plan view thereof; Fig. 3 is a side elevation thereof; Fig. 4 is an end elevation thereof.

I claim:

The ornamental design for a door handle substantially as shown.

RALPH S. ROBERTS.
